UNITED STATES PATENT OFFICE.

GEORGE BORST, OF ROCHESTER, NEW YORK.

SCOOP.

SPECIFICATION forming part of Letters Patent No. 268,452, dated December 5, 1882.

Application filed September 27, 1882. (No model.)

To all whom it may concern:

Be it known that I, GEORGE BORST, a citizen of the United States, residing at Rochester, in the county of Monroe and State of New York, have invented certain new and useful Improvements in Scoops; and I do hereby declare that the following is a full, clear, and exact description of the same, reference being had to the annexed drawings, making a part 10 of this specification, and to the letters and figures of reference marked thereon.

Figure 1 of the drawings is a perspective view, and Fig. 2 a longitudinal vertical section, of a scoop embodying my invention.

This invention relates to certain new and useful improvements in the manufacture of scoops, the objects thereof being to provide a scoop that will be at once cheap, strong, and light in its construction, and from the nature 15 of its composition cannot tear, split, break, or rust, these being the great objections to scoops in which the blade or body thereof is made from wooden or sheet-metal substances; and the invention consists in forming the blade or 20 body of scoops from a composition known as "vulcanized fiber," as hereinafter described and claimed.

In the accompanying drawings, A represents the blade or body portion of a scoop composed of vulcanized fiber attached in any suitable manner to a head, B, preferably formed of light wood, having connected thereto a handle, C. By forming the blade or body portion of vulcanized fiber I produce a scoop that is very 25 light in weight and at the same time possessing great strength, the density of the material employed rendering the article extremely durable, as little or no perceptible wear is incident to its constant use, and from the low 30 cost of this material the scoop can be manufactured and sold much cheaper than wooden or metallic articles of a like character.

Wooden scoops have been found objectionable from their liability to warp and split, while sheet-metal scoops become bent and 45 rusty, and are liable to become punctured by nails or other unyielding substances in barrels or boxes, thereby soon wearing out and becoming useless. Scoops having steel blades, while being strong, and to a certain extent more 50 durable than wooden or sheet-metal articles of a like character, are objectionable on account of their heaviness, and, in common with those composed of sheet metal, are easily affected by rust, thus requiring frequent cleaning in 55 order to prevent discoloration and damage to the goods in which they are used.

This material, known as "vulcanized fiber," being subjected during its manufacture to a great pressure, is necessarily a dense and hard substance, and will not deteriorate by age, but rather improve by seasoning, and being tough and strong will sustain pressure without change of shape or injury, and being a fibrous composition cannot rust. Consequently a scoop made 60 therefrom will of necessity last longer, be lighter of weight, and more easily handled than those made from the materials commonly employed, and at the same time be manufactured and sold at a less cost.

Having now fully described my invention, what I claim as new, and desire to secure by Letters Patent, is—

As an improved article of manufacture, a scoop in which the blade or body is constructed 75 of or formed from vulcanized fiber, substantially as and for the purpose set forth.

In testimony that I claim the above I have hereunto subscribed my name in the presence of two witnesses.

GEORGE BORST.
